ARTICLE CONTAINING AND DISPENSING CASE

Filed Nov. 19, 1926

By Fatty O. Lindemann

Attorney

UNITED STATES PATENT OFFICE.

TEDDY O. LINDEMAN, OF WINONA, MICHIGAN; OTTO C. LINDEMAN, ADMINISTRATOR
OF SAID TEDDY O. LINDEMAN, DECEASED.

ARTICLE CONTAINING AND DISPENSING CASE.

Application filed November 19, 1926. Serial No. 149,506.

My invention relates to an article containing and dispensing case arranged so as to dispense one of the articles contained therein on each successive operation of the device, 5 and aims to provide a novel and improved device of this character which is more especially designed for containing and dispensing sticks of gum or like articles.

With this principal object in view the invention 10 contemplates the provision of a case having a thumb or finger engaging knob projecting therefrom adapted to be moved when the case is arranged in the hand of the user for operating certain mechanism to 15 push a single article partly out of the case so that it may be grasped for removing the same.

By the particular construction and arrangement of parts, as hereinafter specifically described and claimed, I provide a device of the above indicated character which is simple and substantial in construction, can be cheaply manufactured, and will be thoroughly efficient and practical in use.

The invention is illustrated in the accompanying drawings, wherein:

Figure 1 is a perspective view of my improved case, showing in dotted lines the same engaged in a hand of a user,

Figure 2 is a vertical longitudinal section taken through the case at one side thereof,

Figure 3 is a horizontal longitudinal section taken on line 3—3 of Figure 2,

Figure 4 is a cross vertical section taken 35 on line 4—4 of Figure 2, and

Figure 5 is a perspective view of portions of the device removed from the case.

Referring to the drawings the numeral 10 designates a rectangular casing, having 10 side walls 11 and 12, top wall 13, bottom wall 14, and an end wall 15, the other end being closed by a closure plate 16 hingedly connected by pintle 17 to the upper portion of the case. The closed end 15 of the case 40 is provided with an elongated opening 18 through which the articles are adapted to be dispensed.

Arranged within the case is an elongated U-shaped frame 20, secured to the bottom of the case by means of a rivet 19, the bight portion 22 of said frame being spaced from the wall 11 of the case by means of small studs 21 formed on said bight portion, while the outer ends of the upper and lower mem-

bers of said U-shaped frame engage the 55 opposite side wall 12 of the case. The height of this frame is less than the height of the case so that the upper member or plate thereof is spaced a slight distance from the top wall 13 of the case, the object of 60 which will be set forth as the description proceeds.

Cut from the upper member or plate of the elongated U-shaped frame is an ear 23 which extends upwardly and parallel with 65 the bight portion 22, said ear providing for pivotally connecting thereto, at 24, an operating arm 25 arranged for swinging movement between the bight portion of the frame and the wall 11 of the casing, and on 70 the lower end of this arm is a bent portion or pusher 26 working in an arcuate slot 27 in the bight portion 22 of the frame and protruding a sufficient distance within said frame to engage an article contained therein. 75 Slidable on the upper portion of the U-shaped frame is a member 28 preferably constructed of sheet metal and comprising a body portion 29 having a downwardly extending flange 30 riding on the upper portion of said frame, with a depending flange 31 at one side which slidably engages the outer surface of the bight portion 22 of the frame, and a forwardly projecting member 32 projecting into a depression in the top 80 of the case for operating the slide as herein-after explained. The member or slide 28 is connected to the operating arm 25 by means of a link 33, pivotally connected, at 34, to the arm and pivotally connected, at 35, to 85 the depending flange 31 of the slide. It can be seen that when the member 28 is slid within the casing it will swing the arm 25 on its pivot so that the pusher 26 working through the arcuate slot 27 will engage and 90 push one of the articles out of the slot 18.

The upper wall 13 of the casing 10 is depressed adjacent the closed end 15 of the casing, as at 36, the rear wall of said depression having an opening 37 through which 100 extends the forwardly projecting member 32 of the slide, said member being provided with a finger or thumb engaging portion or lip 38 at its free end so as to be easily engaged for operating the slide. It is to be noted that the opening through which the member 32 of the slide 28 extends forms a 105 guide for said member, and that the lip 38

slides in the depression 36 below the top of the casing. The U-shaped frame 20 is adapted to receive the articles to be dispensed and is provided with feeding mechanism 39 for forcing the articles over towards the bight portion 22 of said frame as they are dispensed, said feeding mechanism consisting of a plate 40 arranged between the top and bottom of the U-shaped frame and 5 pivotally connected adjacent the rear end of said frame, as at 41, so that the free end of said plate will engage against the center of the article next to the plate. The plate is held in contact with the articles for feeding 10 the same by means of a coil spring 42, connected to a small lug 43 extending upwardly from the plate and to an upturned flange 44 at the rear end of the U-shaped frame. It can be seen that the coil spring 42 will hold 15 the plate in engagement with the contiguous article so that all of the articles will be yieldably forced towards the bight portion 22 of the U-shaped frame as they are dispensed. Also attached to the lug 43 of the 20 plate 40 is one end of a coil spring 45 the other end of which is attached to the flange 30 of the slide 28 for returning the same to initial position after being operated.

In order to fill the case with sticks of gum 30 or like articles, the closure plate 16 is swung upon its pivot 17 and the articles forced between the portion 22 of the U-shaped frame 20 and the yieldable feeding plate 40, so as to be contained within the U-shaped frame 35 for dispensing them successively on operation of the dispensing mechanism, the hinged closure plate being returned to its position for closing the case. When it is desired 40 to dispense gum from the case, the operator holds the case in one hand so that the thumb rests in the depression 36 in the top wall 13 of the case against the upturned end or lip 38 of the operating member of the slide, and by pressure on this lip said slide will be 45 moved to swing the arm 25 forwardly against tension of the spring 45 so that the pusher at the lower end thereof will engage the stick of gum adjacent the portion 22 of the U-shaped frame 20 and force it partly 50 through the opening 18 in the end wall 15 of the casing. The projecting portion of the stick of gum may then be easily and conveniently grasped for withdrawing the same from the case. When the stick of gum 55 has been withdrawn the plate 40 will force the other sticks of gum within the frame 20 towards the wall 22 so that upon operation of the slide again another stick of gum will be dispensed. It is to be noted that the 60 lateral extension or pusher 26 on the operating arm 25 engages the rear ends of the sticks of gum in forcing them through the opening 18 in the end wall 15 of the case and that said pusher projects through the bight portion of the U-shaped frame a dis-

tance only for engaging one stick of gum at a time, so that upon each operation of the device one stick of gum will be dispensed. It is also to be noted that the lugs 21 carried by the side wall 22 of the U-shaped 70 frame space said side wall from the wall 11 of the case so that the operating arm 25, link 33, and depending flange 31 of the slide 28 may operate freely between said walls.

In the present instance the parts of the 75 device are so constructed and arranged that by removing the rivet 19 which extends through the bottom wall 14 of the casing and the lower side portion of the U-shaped frame the said frame and structure supported thereby may be slid rearwardly through the rear or open end of the case. When removing the operating structure from the case, the outer end of the member 32 of the slide is forced downwardly at the opening 85 37 so that the upturned lip 38 will not interfere with rearward sliding movement of the U-shaped frame and structure carried thereby in the case. It is also to be noted that the opening 18 through which the gum 90 is dispensed is of a size corresponding with the sticks of gum so that only one article may pass therethrough at a time, so as to prevent more than one article being dispensed by frictional contact of one with another, the article next the one being dispensed engaging the front wall of the casing at one side of said delivery slot.

I claim:

1. An article dispensing device comprising 100 a casing having a slot in its forward end through which the article is delivered, a U-shaped frame mounted within the casing having the bight portion thereof spaced from the adjoining side wall of said casing 105 and its upper member below the top of the casing, the bight portion of the frame having an arcuate slot therein, a slide mounted on the frame and having an operating member projecting through the top of the casing, a spring actuating said slide in one direction, an arm pivoted to the rear portion of the U-shaped frame and having a pusher extending through the arcuate slot, and a link connecting the slide to the arm; 115 together with means for pressing the articles against the bight portion of the U-shaped frame.

2. An article dispensing device comprising 120 a casing having a slot in its forward end through which the article is delivered, a U-shaped frame within the casing having the bight portion thereof spaced from the adjoining side wall of said casing and its 125 upper member below the top of the casing, the bight portion of the frame having an arcuate slot therein, a slide mounted on the frame and having an operating member projecting through the top of the casing, a spring actuating said slide in one direction, 130

an arm pivoted to the rear portion of the **U**-shaped frame and having a pusher extending through the arcuate slot, and a link connecting the slide to the arm; together with 5 a plate pivoted at the open end of the **U**-shaped frame with the free end of the plate bearing against the center of the articles to force them against the bight portion of said frame, and a spring for forcing the 10 plate against the articles.

3. An article dispensing device comprising a casing having a slot in its forward end through which the article is delivered and open at its rear end, a **U**-shaped frame in 15 the casing with the bight portion thereof on a line with one side of the slot and having an arcuate slot therein, an arm pivoted to the frame and having a pusher working through the arcuate slot to eject an article 20 through the slot in the forward end of the casing, a slide mounted on the frame and having an operating member projecting through the casing, and a link connecting the slide to the arm for operating the latter; together with means for feeding the 25 articles against the bight portion of the **U**-shaped frame comprising a plate pivoted to the rear portion of the **U**-shaped frame with the free end thereof bearing against the center portion of the article, and a spring 30 connected to the plate and to the frame for pressing the free end of the plate against

the articles contained within the said **U**-shaped frame.

4. An article dispensing device comprising 35 a casing having a slot in its forward end through which the article is delivered and a depression in its top with an opening through the rear wall and bottom of said depression, a **U**-shaped frame in the casing 40 having the bight portion spaced from the adjoining side wall of the casing and its upper member spaced from the top of the casing, a slide movable between said upper member of the frame and top of the casing 45 and having an operating member extending into the depression in the top of the casing through the aforesaid opening in the rear wall and bottom thereof, an ejector-arm pivoted to the **U**-shaped frame and having a pusher working through the arcuate slot in the bight portion thereof, and a link connecting the ejector-arm to the slide; together with a plate pivoted between the 50 upper and lower members of the **U**-shaped frame with the free end thereof bearing against the center portion of the articles contained in said frame, and a spring for 55 forcing the free end of the plate against the articles to press them against the bight portion of the frame.

In testimony whereof, I have affixed my signature.

TEDDY O. LINDEMAN.
